UNITED STATES PATENT OFFICE.

GUSTAV A. J. JOETTEN AND JOHN MITTEL, JR., OF CHICAGO, ILLINOIS.

DESIGN FOR A FRAME FOR VEGETABLE-CUTTERS.

SPECIFICATION forming part of Design No. 25,456, dated May 5, 1896.

Application filed August 15, 1895. Serial No. 559,427. Term of patent 7 years.

To all whom it may concern:

Be it known that we, GUSTAV A. J. JOETTEN and JOHN MITTEL, Jr., citizens of the United States, residing at Chicago, in the county of Cook and State of Illinois, have invented a certain new and original Design for Vegetable-Cutter Frames; and we do declare the following to be a full, clear, and exact description of the invention.

Our invention relates to a new design for frames for vegetable-cutters.

Our new design consists of a frame for a vegetable-cutter of the configuration and ornamentation shown in the accompanying drawing, in which we have represented the frame in perspective.

The leading features of the design are a flat upwardly-extending standard 1, having parallel rows of apertures 2, a semicircular base

3, laterally-projecting arms 4, a semicircular hollow body 5, projecting laterally from the upper end of the standard, a rectangular head 6, supported by the body and having a curved under side, a rectangular box 7, and a cap 8, supported by the box and having a knob 9. A frame thus constructed is both neat and ornamental in appearance and pleasing to the eye.

What we claim is—

The frame for a vegetable-cutter, as herein shown and described.

In testimony whereof we affix our signatures in presence of two witnesses.

GUSTAV A. J. JOETTEN.
JOHN MITTEL, JR.
